ELECTRIC SWITCH

Philip Hutt, New Haven, Conn., assignor to General Electric Company, a corporation of New York

Application March 23, 1939, Serial No. 263,695

9 Claims. (Cl. 200—54)

This invention relates to electric switches of the type having liquid contact circuit controllers for controlling the flow of current through the switch.

The object of the invention is the provision of an improved construction and arrangement in switches of this type which may be easily assembled and manufactured at low cost.

In the accompanying drawing Fig. 1 illustrates one use to which the switch may be put; Fig. 2 is a sectional view through the switch; Fig. 3 is a sectional view along the lines 3—3 of Fig. 2; Fig. 4 is a view of the interior of the switch; Fig. 5 is a sectional view along the line 5—5 of Fig. 4; and Fig. 6 is a view showing the construction and operation of the liquid contact circuit controller.

Referring to the drawing, and more particularly to Fig. 6, the invention has been illustrated using a liquid contact circuit controller C having a pair of cup-shaped metal terminals 1 which are separated by an insulating diaphragm 2 of a refractory material, such as a ceramic material. The edges of the terminals are sealed by a bead 3 of glass which also seals the junctions between the diaphragm and the terminals. Within the space enclosed by the terminals is a suitable quantity of mercury 4 which forms the conducting medium between the terminals. In the manufacture of the circuit closer the space enclosed by the terminals is evacuated and filled with hydrogen at a pressure of one or more atmospheres which increases the current-interrupting capacity of the circuit closer. As shown by the full lines in Fig. 6, the diaphragm 2 is provided with an opening 5 which is submerged in the mercury 4 when the circuit controller is in the current-conducting position. When the circuit controller is in the current-interrupting position, shown in dotted lines in Fig. 6, the opening 5 is above the mercury and the circuit between the terminals is therefore broken by the insulating diaphragm 2. Due to the construction of the circuit controller the interruption of the circuit between the terminals takes place in the mercury as the circuit closer is turned so that the opening 5 in the diaphragm approaches the dotted line position. This construction is illustrative of liquid contact circuit controllers which are suitable for use in a switch embodying this invention.

The switch in Figs. 1 to 5, inclusive, has a frame comprising spaced longitudinal bars 10 supported at one end by a base 11 of insulating material and at the other end by a plate 12. The bars 10 and the plate 12 may be formed of sheet metal. Supporting elements for the liquid contact circuit controller are mounted on each side of the base

11 and are formed of metal straps having blades 13 gripping the terminals of the circuit controller and bent ends 14 providing terminals for receiving the terminal screws 15. Each of the blades 13 is provided with a substantially circular projection 16 which engages a corresponding cup-shaped terminal of the circuit closer. This forms a bearing structure for rotatably mounting the circuit closer. The supporting blades 13 are insulated from the bars 10 by plates 17 formed, for example, of sheet fiber insulating material and the bars 10, plates 17 and blades 13 are held in assembled relationship on the base 11 by a rivet 18, or other suitable fastening means. In order to insulate the blades 13 one from the other, the rivet 18 is covered with a sleeve 19 of insulating material. The terminal screws are separated from one another by a barrier 20 projecting integrally from the base 11.

Operating means for the circuit controller includes a pin 21 which is slidably mounted in the plate 12 and in a cross-bar 22 spanning the longitudinal bars 10 between the base 11 and plate 12. At one end the pin is provided with a head 23 which cooperates with a coiled spring 24 surrounding the pin and which is compressed between the head and the cross-bar 22. A cap 25 encloses the headed end of the pin and conceals the spring 24. At the other end, the pin is of reduced cross-section, as shown at 26, and carries two disks 27 of insulating material disposed between a washer 28 and the peened over end 29 of the pin. An operating element, for example a spring 30, is attached to the pin 21 by being formed with an offset portion 31 clamped between the insulating disks 27. The spring is substantially U-shaped and is provided with arms 32 and 33 extending toward the liquid circuit controller. The arm 32 is provided with a bent end 34 extending through an opening in a disk 35 mounted on one of the terminal members of the circuit controller; disk 35 is provided with a central opening to form, in effect, an annulus so that it may be slipped on to one of the terminals of the circuit controller for frictional engagement therewith.

The disk 35 may be made of insulating material, such as sheet fiber, but this is not necessary as the spring is electrically connected to the circuit controller as will appear hereinafter. By this arrangement longitudinal movement of the pin 21 and spring 30 produces rotational movement of the disk 35.

In order to provide for rotation of the circuit closer the disk 35 is keyed to the former by means of a projection 36 seated within a recess or key-

way 37 formed in the terminal of the circuit closer. This means that longitudinal movement of the pin 21 is translated into rotative movement of the liquid contact circuit closer which rotates about the bearings 16. Rotation of the circuit controller moves the bent end 34 of the spring in an arcuate path parallel to the outer periphery of the circuit controller and, since the other end of the spring is fixed to the pin 21 the arm 32 is made flexible to take care of the lateral movement of the bent end relative to the pin 21. This means that the structure translating reciprocatory movement of the pin 21 into rotative movement of the circuit controller is greatly simplified inasmuch as it is unnecessary to provide a pivot bearing for the arm 32 at its point of connection with the pin 21 such as would be required if the arm 32 were a rigid member. Flexure of the spring arm 32 produces a slight lateral component of force on the circuit controller in a downward direction, in the showing of Fig. 2. This force is overcome by extending the other spring arm 33 into engagement with the other side of the circuit closer where the end of the arm is flared outwardly, as shown at 38, and rests upon the terminal member of the circuit closer. This means that upon longitudinal movement of the pin 21 both the spring arms 32 and 33 are flexed outwardly, or spread apart, the arm 32 rotating the circuit controller and the arm 33 counterbalancing the component of force induced by the arm 32 with the flared end 38 sliding over the terminal of the circuit controller.

The switch mechanism thus far described may be placed as a unit within a protective casing or shell 39 having a lining sleeve 40, of insulating material. At one end the casing is provided with an opening 41 for receiving the conductors to be connected to the switch terminals and at the other end the casing is flared outwardly, as shown at 42, and closed by a face plate 43 secured in position by screws 44. The base 11 of the switch mechanism rests upon the inner wall of the insulating shell while a portion of the mounting plate 12 is clamped between the end of the casing and the face plate 43, as shown at 45. In this manner the switch mechanism is mounted securely within the casing with the pin 21 and cap 25 extending outwardly beyond the confines of the casing through an opening 46 formed in the face plate.

The opening 5 in the ceramic barrier and the keyway 37 in the terminal of the circuit controller may be so arranged that the switch may be operated in either a normally "off" or "on" position. In the form of the invention illustrated by Fig. 2, the switch is in "on" position when the plunger pin 21 is in extended position. Manifestly, the keyway may be so placed on the circuit controller that the switch is in "off" position when the plunger is extended.

One of the uses to which the switch may be put is as a door switch. This use is illustrated by Fig. 1. The switch is mounted on the jamb 47 by means of the face plate so that as the door 48 is opened and closed it reciprocates the pin 21 causing rotation of the circuit controller to control the electrical circuit through the switch. The spring 24 forces the pin to extended position when the latter is released by the door.

The flexible spring arms 32 and 33 provide a simple and effective means for interconnecting the rotatable circuit closer and reciprocatory pin. The arms may be made of light spring wire and give a very smooth operation of the circuit con-

troller. By counter-balancing the lateral component of force induced by the slight flexure of the arm 32, the arm 33 maintains the circuit closer seated securely upon the bearing surfaces 16 and reduces wear at those points. While the 5 spring arms 32 and 33 have been shown and described as forming integral parts of the spring 30, it should be manifest that the arms may be formed of separate elements. In some cases, the counterbalancing spring arm 33 may be omitted 10 although this arm has been shown and described as a preferred form of the invention. Inasmuch as the flared end of the arm 33 bears against one terminal of the circuit controller, this arm is in electrical connection with one part of the 15 circuit controller so that it is desirable to insulate the arm from the switch-operating mechanism, particularly the operating pin 21. This is accomplished by the insulating disks 27 which support the spring 30 and the arms 32 and 33 20 upon the operating pin and at the same time insulate the latter from the spring arms. The portion of the spring gripped by the disks is spaced from the central reduced portion 26 of the pin, by being curved around the pin, as shown by 25 Fig. 3.

What I claim as new and desire to secure by Letters Patent of the United States is:

1. In an electric switch, a liquid contact circuit controller operable by rotation about its 30 axis, a disk keyed to said circuit controller, an operating pin slidably mounted for reciprocatory movement, and a flexible spring arm interconnecting said operating pin and disk for translating reciprocating movement of said pin into 35 rotation of said circuit controller.

2. In an electric switch, a liquid contact circuit controller operable by rotation about its axis, a member keyed to said circuit controller, an operating pin slidably mounted for reciprocatory 40 movement, and a flexible spring member pivotally connected at one end to said first-mentioned member and being fixed at the other end to said pin for translating reciprocating movement of said operating pin into rotation of said circuit 45 controller.

3. In an electric switch, a liquid contact circuit controller operable by rotation about its axis, an element slidably mounted for reciprocatory movement, and a flexible spring member pivotally connected at one end to said circuit controller and being fixed at the other end to said element for translating reciprocating movement of said element into rotation of said circuit controller. 55

4. In an electric switch, a liquid contact circuit controller operable by rotation about its axis, an operating element slidably mounted for reciprocatory movement, a flexible spring arm, one end of said spring arm being secured to said reciprocating element and the other end being connected to said circuit controller on one side of its axis and a second spring arm connected at one end to said element and bearing against said circuit 60 controller on the other side of its axis.

5. In an electric switch, a liquid contact circuit controller operable by rotation about its axis, a disk keyed to said circuit controller, an operating pin slidably mounted for reciprocatory movement, a flexible spring arm, one end of said spring arm being secured to said reciprocating pin and the other end being connected to said disk on one side of the axis of said circuit controller, and a second spring arm connected at one end to said 70

element and bearing against said circuit controller on the other side of its axis.

6. In an electric switch, a base of insulating material having spaced contact blades mounted thereon, a liquid contact circuit controller pivotally supported by said blades for rotation about its axis, a reciprocatory operating element, a member of insulating material keyed to said circuit controller, and a flexible spring arm fixed at one end to said operating element and being pivotally connected to said insulating member at the other end for rotating said circuit controller upon movement of said element.

7. In an electric switch, a base of insulating material having spaced contact blades mounted thereon, a liquid contact circuit controller pivotally supported by said blades for rotation about its axis, a reciprocatory operating element, a member keyed to said circuit controller, a flexible spring arm, one end of said spring arm being secured to one end of said reciprocatory element and the other end being secured to said member on one side of the axis of said circuit controller, and a second spring arm connected at one end to said reciprocatory element and bearing against said circuit controller on the other side of its axis.

8. An electric switch comprising longitudinally spaced bars, a base of insulating material supported at one end by said bars, transverse members supported between said bars at their other

ends, spaced contact blades mounted on said base and disposed between said bars, a liquid contact circuit controller pivotally supported on said blades for rotation about its axis, an operating element slidably mounted in said transverse members for reciprocatory movement, a member keyed to said circuit controller, and a flexible spring arm secured at one end to said slidably element and being pivotally connected to said insulating member at the other end for rotating said circuit controller upon movement of said element.

9. An electric circuit comprising longitudinally spaced bars, a base of insulating material supported at one end of said bars, transverse members supported between said bars at their other ends, spaced contact blades mounted on said base between said bars, a liquid contact circuit controller pivotally supported by said blades for rotation about its axis, an operating element slidably mounted on said transverse elements for reciprocatory movement, a member keyed to said circuit controller, a flexible spring arm, one end of said spring arm being secured to said slidably element and the other end being connected to said insulating member on one side of the axis of said circuit controller, and a second spring arm connected at one end to said slidably element and bearing against said circuit controller on the other side of its axis.

PHILIP HUTT.
